(57) **CLAIM**

The ornamental design for a tamper evident closure, as shown and described.

DESCRIPTION

FIG. 1 is an upper perspective view of the tamper evident closure.

FIG. 2 is a cross-section view of the tamper evident closure taken in a direction of line 2-2 of FIG. 1.

FIG. 3 is a front view of the tamper evident closure, taken from within portion “3” of FIG. 1.

FIG. 4 is a bottom view of the tamper evident closure, taken from within portion “4” of FIG. 1.

FIG. 5 is a left view of the tamper evident closure, taken from within portion “5” of FIG. 1.

FIG. 6 is a right view of the tamper evident closure, taken from within portion “6” of FIG. 1.

FIG. 7 is a lower perspective view of the tamper evident closure of FIG. 1.

FIG. 8 is a rear view of the tamper evident closure, taken from within portion “8” of FIG. 7; and,

FIG. 9 is a lower perspective view of the tamper evident closure, taken from within portion “9” of FIG. 7.

The dash-dash broken lines represent portions of the tamper evident closure that form no part of the claimed design. The dash-dot broken lines represent the designation of detail views and form no part of the claimed design.
